UNITED STATES PATENT OFFICE.

ELMER B. REED, OF PITTSBURGH, PENNSYLVANIA.

HATCHET.

Application filed January 19, 1925. Serial No. 3,426.

To all whom it may concern:

Be it known that I, ELMER B. REED, a citizen of the United States, residing at Pittsburgh, in the county of Allegheny and State 5 of Pennsylvania, have invented a new and useful Hatchet, of which the following is a specification.

This invention relates to tools and more particularly to hatchets.

10 The object of the invention is to provide a nail extracting hatchet equipped with opposing jaws on either side of the eye thereof and having nail engaging apertures formed in said jaws, so arranged that the strain is 15 brought to bear on the flat side of the hatchet and also of the handle.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings:

Figure 1 represents a side elevation of a hatchet constructed in accordance with this 30 invention, a portion of the handle being broken off for convenience in illustration;

Fig. 2 is an end elevation of the hatchet;

Fig. 3 is a detail longitudinal section partly in elevation showing the eye of the 35 hatchet with the handle inserted therein; and

Fig. 4 is a section taken on the line 4—4 of Fig. 3.

In the embodiment illustrated a hatchet head 1 is shown equipped with the usual 40 eye 2 for receiving the handle 3. The opposed side walls of the eye 2 at the outer ends thereof are provided with notches 4 and 5 to form nail receiving jaws. These notches are shaped to conform to the head 45 and adjacent portion of a nail so that the same may be readily engaged therewith so that the strain employed in pulling or extracting the nail is exerted on the broad portion of the handle as well as of the head. 50 The handle 3 terminates flush with the outer wall or edge of the eye hatchet head as is shown clearly in Figs. 1 and 3. Aside from these jaws formed by the notches 4 and 5 the hatchet head is the same as those of ordinary 55 construction.

I claim:

A nail extracting hatchet having a handle receiving eye with recesses in its opposed side edges at the outer ends thereof, said 60 recesses conforming substantially in shape to that of the head and adjacent portion of a nail and opening inwardly to receive the nail for extracting it, the strain being born by the broad side of the hatchet head and 65 by the handle.

In testimony that I claim the foregoing as my own, I have hereto affixed my signature in the presence of two witnesses.

ELMER B. REED.

Witnesses:

G. L. LIDDELL,
EARL F. REED.
